(57) **CLAIM**

The ornamental design for an orthopedic device for stabilizing the thumb, as shown and described.

DESCRIPTION

FIG. 1 is a front view of an orthopedic device for stabilizing the thumb, showing our new design, in open condition;

FIG. 2 is a back view thereof;

FIG. 3 is a top perspective view thereof, in use condition on the right hand;

FIG. 4 is a bottom perspective view thereof, in use condition on the right hand;

FIG. 5 is a top perspective view thereof, in use condition on the left hand; and,

FIG. 6 is a bottom perspective view thereof, in use condition on the left hand.

The broken line showing of the hand in FIGS. 3-6 is for illustrative purposes only and forms no part of the claimed design.

1 Claim, 4 Drawing Sheets

FIG. 1

FIG. 2

FIG. 4

FIG. 3
